US00D894288S

(12) **United States Design Patent** (10) Patent No.: **US D894,288 S**
Shapiro et al. (45) Date of Patent: **** Aug. 25, 2020**

(54) **BUBBLE MACHINE**

- (71) Applicant: **Honor Metro Limited**, Tsim Sha Tsui, Kowloon (HK)
- (72) Inventors: **Ami Shapiro**, Woodland Hills, CA (US); **Xiaoyi Zhang**, Pasadena, CA (US); **Jeffrey Falerni**, Agoura Hills, CA (US)

- (73) Assignee: **Honor Metro Limited**, Tsim Sha Tsui (HK)

(**) Term: **15 Years**

(21) Appl. No.: **29/670,991**

(22) Filed: **Nov. 21, 2018**

(51) LOC (12) Cl. **21-01**
 (52) U.S. Cl.
 USPC **D21/401; D21/421**

(58) **Field of Classification Search**

USPC D21/398, 401, 402, 405, 455, 468, 483, D21/513, 514, 516, 523, 525, 526, 528, D21/532, 414, 419, 421-435, 457, D21/533-563; 446/15-21, 71, 74, 76, 446/475, 484, 487, 491, 431, 440, 444, 446/448-453

(57) **CLAIM**

The ornamental design for a bubble machine, as shown and described.

DESCRIPTION

FIG. 1 is a front perspective view of a bubble machine showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the bubble machine that form no part of the claimed design.

1 Claim, 7 Drawing Sheets
